UNITED STATES PATENT OFFICE.

JAMES W. LEMON, OF HARDY, ARKANSAS.

MACHINE FOR DESTROYING INSECTS.

1,202,860.

Specification of Letters Patent. Patented Oct. 31, 1916.

Application filed June 26, 1916. Serial No. 105,906.

To all whom it may concern:

Be it known that I, JAMES W. LEMON, a citizen of the United States, residing at Hardy, in the county of Sharp and State 5 of Arkansas, have invented new and useful Improvements in Machines for Destroying Insects, of which the following is a specification.

This invention is an improved machine 10 for destroying insects and which can be also used as a vacuum cleaner for taking up dust and the like, the object of the invention being to provide an improved machine of this character which is simple in construction, which may be readily moved from place to place, from one room to another, and to and from a porch, or the like, and which may be driven by a suitable motor and kept for a long time in continuous operation.

20 The invention consists in the features of construction, combination, and arrangement of devices, hereinafter fully described and claimed.

Figure 1 is a side elevation of an insect 25 destroying machine constructed and arranged in accordance with my invention. Fig. 2 is a plan of the same. Fig. 3 is a vertical sectional view.

The main frame 1 is mounted on axles 2, 3, 30 provided respectively with wheels 4, 5, and said main frame comprises longitudinal side bars 6, transverse front and rear cross bars 7, and 8, intermediate cross bars 9, and an intermediate longitudinal bar 10. A fifth 35 wheel 11 is preferably provided for the front axle and the same is also preferably provided with a steering device 12. The width of the frame is such as to enable the machine to be readily drawn through an ordinary 40 door way from one room to another or from a room to the porch or the like.

A suitable platform 13 is on the rear portion of the main frame and supports a suitable motor 14 which is here indicated as an 45 internal combustion engine and as provided with a shaft 15 having fly wheels 16 and a pulley 17. Frames 18 are secured on the sides of the main frame at a point midway between the front and rear ends thereof and 50 are provided with bearings for the shaft 19 of a rotary fan 20. The said fan comprises radial arms 21 and fan plates 22 which are bolted on the arms. The fan revolves in a

casing 23 which is secured to the frames 18 and said casing is provided on its sides with 55 valves 24. A metallic elbow 25 is secured on the casing at a suitable point and is adapted for the attachment of a flexible intake tube 26 which may be directed upwardly and is provided at its free or upper 60 end with a funnel shaped spout 27 adapting the machine for use in removing by suction cobwebs or the like from ceilings and walls.

A suction pipe 28 also extends downwardly from the fan casing to within a short 65 distance of the floor and is provided at its lower end with a spout 29 which has a hinged member 30 on one side. A discharge tube 31 is connected to the upper side of the fan casing as at 32 and discharges into a 70 tank 33 which may contain water or a poisonous solution or other suitable liquid or insecticide.

A countershaft 34 is mounted in bearings 75 on the frames 18 and is provided with a pulley 35 which is connected by an endless belt 36 with a smaller pulley 37 on the fan shaft. The countershaft also has a pulley 38 which is smaller than the lower pulley 17 and is connected thereto by an endless belt 80 39. Hence the fan is driven at a high rate of speed by the motor.

To use the machine for destroying insects, a sweet or other suitable bait is placed near the intake valves 24, the elbow 25 and suction pipe 28 are cut off by the cutoff valve with which they are provided, and the motor is started and caused to revolve the fan. The flies or other insects attracted by the sweetened or other suitable bait are carried 90 into the fan casing through the valves 24 and blown by the blast from the fan through the pipe 31 and into the tank 33 where they are destroyed. If desired, the machine can be kept in operation over night or throughout 95 an entire day or for any other suitable time and thus entirely rid the house or other place of noxious insects. By closing the valves 24 and opening the valve in the pipe 28 and running the machine over the floor, 100 the dust and dirt will be sucked up therefrom through said pipe 28 and blown by the fan into the water in the tank. The machine may also be used for removing potato bugs from growing plants and destroying such 105 bugs.

Having described the invention, what is claimed is:

In apparatus of the class described, a vehicle, a fan casing thereon having valves in one side to admit insects thereto, a tank on the vehicle, a pipe discharging from the valve casing to the tank, a revoluble fan mounted in the casing and having a shaft, a motor mounted on the vehicle and having

a drive shaft, a countershaft, also mounted on the vehicle and power transmission devices connecting the drive shaft of the motor with the countershaft and power transmission devices connecting the countershaft with the fan shaft. 15

In testimony whereof I affix my signature.

JAMES W. LEMON.
